UNITED STATES PATENT OFFICE.

THOMAS LEE, OF HOME CITY, OHIO.

VENTILATOR.

No. 910,398.

Specification of Letters Patent.

Patented Jan. 19, 1909.

Application filed March 19, 1908. Serial No. 422,007.

To all whom it may concern:

Be it known that I, THOMAS LEE, a citizen of the United States, and residing at Home City, Hamilton county, State of Ohio, have 5 invented certain new and useful Improvements in Ventilators; and I do declare the following to be a clear, full, and exact description of the invention, attention being called to the accompanying drawing, with 10 the reference characters marked thereon, which forms also a part of this specification.

This invention relates to ventilators generally used on roofs and where they are provided with means to control and regulate 15 their action.

The invention consists of certain improvements in the construction of the general parts and of the operating members and manipulating means of such ventilators, all as described and claimed hereinafter and as illustrated in the accompanying drawing, in which:

Figure 1, shows in a vertical cross-section my improved ventilator in position. Fig. 2, 25 shows the same in a similar view, partly in elevation and partly in section, view and section being taken on a plane at right angles to the view shown in the preceding figure. Fig. 3, shows part of the under-side of a device or 30 damper whereby the action of the ventilator is controlled and as the same appears in Fig. 1, the view being a section taken substantially below said damper. Fig. 4, is a similar view taken at a lower plane and shows 35 part of an underside view of the ventilator as it appears in Fig. 1, it being more particularly the lower end of the flue. Fig. 5, in side-elevation and Fig. 6, in top-view show 40 in detail a modified construction of certain locking means.

In the drawing, 8 indicates the roof of a building or inclosure to be ventilated. An opening is provided therein where the ventilator is to be applied. This latter consists 45 substantially of a tubular flue 9 of a height and diameter appropriate to suit particular conditions. This flue is mounted above the opening in the roof, a collar 10 being usually interposed upon which the flue is slipped and 50 which collar is provided with a flange 11 for its attachment to the roof. A conical hood 12 to keep the weather out is provided above the flue. It is of larger diameter than this latter and spaced from the upper end of the 55 same. Discharge from the ventilator takes place between the upper edge of the flue and

the lower edge of this hood. To prevent interference with the action of the ventilator by wind-currents, a wind-shield 13 is provided which is substantially an annular 60 band, sustained opposite the space between flue and hood and spaced from both. Brackets 14 are provided to support the hood above the flue and also to sustain shield 13 opposite them. For such purpose these brackets are 65 shaped as shown, their lower ends *a* being attached to the outside of the flue and their upper ends *b* are turned inwardly and under hood 12 to which they are connected. Between their ends these brackets are bent outwardly as shown at *c* to permit connection 70 thereat of the wind-shield. Rivets or bolts 15 serve at all these points as attaching mediums.

Above the upper end of the flue 9 and below hood 12 there is a damper or cap 16 movably supported, so that it may occupy either a raised position as shown in Fig. 1, or a lowered position as shown in Fig. 2, whereby in the latter case the flue becomes closed and 75 the action of the ventilator ceases. This cap is also of conical shape so that, when raised as shown in Fig. 1, it may move well up into the space below hood 12 and its diameter is such that its lower edge extends all 80 around beyond the upper edge of the flue. At this lower edge of the cap there is a vertical flange 17 which, when the cap is in its lowest position as shown in Fig. 2, is adapted to seat upon an inclined rim 18 which is attached to the upper edge of the flue and extends outwardly and downwardly therefrom. When the cap is thus seated upon this rim, 85 no part of it comes in contact with the flue and any moisture, due to condensation, 90 which forms on the underside of the cap is thus diverted to the outside of the flue and drains upon said rim from which it may drip onto the roof. For manipulating this cap I provide a set of toggle-levers 19, connected at their upper end to a bar 21, the 95 ends of which are bent to form flanges 22 whereby the same is attached to the underside of the cap. The connection to this bar is by a pin or bolt 23, which is rigidly attached to said bar and forms also the movable pivot of the toggle-lever set, links 24 of the set serving to connect it to this pivot. The connection at the lower end is to a bar 100 25 which extends across the flue and attaches at its ends, which are bent as shown at 105 26, to the inside of the flue-wall. By lo-

cating the various parts accordingly, these ends 26 and the lower ends *a* of two of the brackets 14 may be brought together in a manner that one bolt-connection may serve 5 for the purpose, bolts 15 thereat being so used. A pin or bolt 27 is mounted on this bar and constitutes the fixed pivot for the toggle-lever-set, the lowermost pair of these levers being mounted thereon.

10 It will now be seen that by means of a suitable manipulating or pull-device, attached to the lower end of the toggle-lever-set by means of interposed links 28, cap 16 may be readily manipulated. Strictly speaking, this manipulation involves merely a raising of the cap, since it normally seeks to occupy a seated position induced by its weight and by the weight of the toggle-levers which tend to close up. See Fig. 2
15 and note also dotted lines in Fig. 1.

20 As a means to hold cap 16 in a manner to move in proper direction with respect to the upper end of the flue and to and from its seat upon rim 18, a rigidly connected, up-right guide-bar 29 is provided for the purpose, substantially in the center of the ventilator. This guide is connected at its upper end to the underside of hood 12 and depends from there down into the flue, the cap being 25 perforated to clear it. For the purpose of its connection to hood 12, it is split longitudinally at its upper end, the separated portions being turned in opposite directions so as to form flanges 31 as shown, which permit 30 application of bolts for connection. Below, it is steadied by connection to bar 25, bolt 27, which constitutes the fixed pivot for the toggle-lever-set, serving also for the purpose of this connection. The cap in part is 35 guided by the perforation in it through which this guide-bar extends in addition to which a bearing 32 is provided, attached to bar 21 and closely fitted around the guide-bar (see Fig. 3).

40 Cap 16 has, as before stated, a normal tendency to occupy its lowest or seated position in which the ventilator is closed. It is therefore necessary to manipulate the same for lifting only. This is done by action on 45 the lower end of the toggle-lever-set where a chain 33 is attached to the ends of links 28 thereat and where they come together. After the cap is raised it is necessary to hold 50

it so against its normal tendency to seat. For such purpose the chain is arranged to pass through a slot 34, provided in a bracket 35. A stop 36 is provided on the chain larger than it and so located thereon that when the toggle-levers are extended in operative position and have raised the cap, it is 55 immediately below bracket 35 as shown in Fig. 1, and where it is held because it is too large to pass through the slot thereat. At one end the slot is enlarged as shown at 37. When the cap is to be lowered and dropped 60 upon its seat to close the ventilator, chain 33 is released by being pulled first to one side as shown in dotted lines in Fig. 2 and until stop 36 is below the enlarged opening 37, through which it is free to pass upwardly 65 as soon as release of chain 33 permits the weight of the dropping cap to exert itself. Similar manipulation takes place when the cap is to be raised again, the chain being pulled through enlarged opening 37 until 70 stop 36 is below bracket 35, after which the chain is drawn sidewise into slot 34. To facilitate the passage of stop 36 through this opening, means are provided to guide it into the same. As shown in Figs. 1 and 2, this is 75 accomplished by shaping the stop conical. In Figs. 5 and 6, a funnel-shaped guide 38 is provided around opening 37, on the upper side of bracket, which guides the ball-shaped stop in proper direction.

Having described my invention, I claim as new:

In a ventilator, the combination of a flue, a hood above the same, a cap adapted to normally seat to close the flue, a guide-bar for this cap attached at its upper end to the hood from which it depends vertically down into the flue, its lower end being bent up to form an angular bracket, mechanism to raise this cap, a chain to manipulate this mechanism and a stop on this chain adapted to engage the bracket mentioned when the cap is raised, thereby holding the same in such position.

In testimony whereof, I hereunto affix my signature in the presence of two witnesses.

THOMAS LEE.
